UNITED STATES PATENT OFFICE.

JAMES A. NORTON, OF ODEBOLT, IOWA, ASSIGNOR, BY DIRECT AND MESNE ASSIGNMENTS, TO GOLDEN WEST PUMP COMPANY, OF SIOUX FALLS, SOUTH DAKOTA, A CORPORATION OF SOUTH DAKOTA.

PUMP.

1,242,842.

Specification of Letters Patent.

Patented Oct. 9, 1917.

Application filed May 11, 1916. Serial No. 96,799.

To all whom it may concern:

Be it known that I, JAMES A. NORTON, a citizen of the United States, residing at Odebolt, in the county of Sac and State of Iowa, have invented certain new and useful Improvements in Pumps, of which the following is a specification.

This invention relates to pumps and particularly to the operating means therefor.

One object is to provide a means for operating pumps of the character employed in raising water from deep wells or mining or irrigation operations where a continuous stream or volume of water is generally desirable.

Another object resides in the provision of means operable to operate the pump in which the means for accomplishing the purpose performs its functions with a minimum amount of power.

Another object of the invention is to provide a pump embodying means to temporarily relieve the load so as to facilitate starting the pump and which load relieving means may be subsequently operated so that the pump may lift to its full capacity.

With the above and other objects in view, the present invention consists in the combination and arrangement of parts herein- 30 after more fully described, illustrated in the accompanying drawings, and particularly pointed out in the appended claims, it being understood that changes may be made in the form, size, proportion and minor de- 35 tails without departing from the spirit or sacrificing any of the advantages of the in- vention.

In the drawings:

Figure 1 is a front elevation of a pump 40 constructed in accordance with one embodiment of my invention, parts being broken away.

Fig. 2 is a side elevation, parts being broken away.

Fig. 3 is a plan view.

Fig. 4 is an enlarged side elevation of the piston operating means with one-half of the housing removed.

Fig. 5 is a horizontal section of the same.

Fig. 6 is an enlarged plan view of one of the valves.

Fig. 7 is an enlarged vertical section of the same with one of the valves lifted.

Fig. 8 is a detail perspective view of one of the cross heads.

Referring now more particularly to the accompanying drawings, the reference character 8 indicates a base which may be composed of any suitable material and of any suitable formation and which is provided with apertures 9, 10 and 11 for a purpose presently explained.

A pump cylinder 12 is mounted in any suitable manner below the base 8. This pump cylinder 12 is preferably solid at its 65 upper end, as indicated at 13, and at its upper end exteriorly screw threaded for working fit with the interiorly screw threaded boss 14 on the under side of the base 8, said solid portion 13 having a bore 70 15 alining with the aforesaid aperture 11 of the base.

A discharge outlet or spout 16 extends laterally from the pump cylinder at the outer end thereof and preferably immediately below the solid portion 13 of the cylinder. The pump cylinder at a point adjacent the lower end thereof is provided with openings 17, these openings being of any suitable form but, as shown, being in 80 the form of relatively short spaced slots. These openings are arranged preferably slightly above the water line and are normally closed by a sleeve 18 which slidably embraces the pump cylinder. An arm 19 is 85 connected to the sleeve 18 and the arm in turn is connected with the offset end 20 of a controlling bar 21 slidable through a slot 22 in the base 8.

The controlling bar 21 is provided with 90 teeth 23 with which coacts a spring controlled pivoted dog 24 mounted on the base 8 so as to hold the controlling bar 21 and consequently the sleeve 18 in adjusted positions with relation to the openings 17 in the 95 pump cylinder. To facilitate operation of the controlling bar 21 the same may be provided with a suitable handle 25. The purpose of sliding this sleeve over and away from over the openings 17 will be later explained.

Three open-ended pistons 26, 27 and 28 are located in the pump cylinder and each piston is provided with suitable check valves adapted to open and close upon the up and 105 down strokes thereof. In the present in-

2
stance each piston is provided with a transverse web 29 at its upper end to which flap valves 30, preferably of segmental shape, are hingedly connected and which at their free edges rest preferably on the upper end of the respective piston. These pistons are adapted to reciprocate in paths which overlap each other and in circles an equal distance apart, say for instance, 120°. At all times at least one of the pistons will be on the upstroke and the lowermost piston 28 is located below the aforesaid openings 17, traveling below the surface of the water.

10 The lowermost piston 28 is supported in the pump cylinder in any suitable manner but, as shown, it is supported on parallel rods 31 and 32 arranged parallel with the pump cylinder and exteriorly thereof, reciprocating through suitable guides 33 and 34, respectively, projecting from the lower end of the pump cylinder. The lower ends of these parallel rods 31 and 32 are connected by a cross piece 35 in any suitable manner and to this cross piece 35 is a short supporting upright 36 to which the lowermost piston 28 is connected. The upper ends of these rods 31 and 32 reciprocate through the opposite apertures 9 and 10 in the base 8 and at their upper ends they are connected in any suitable manner to the cross head 37 15 slidable on guide rods 40 and 41, respectively, which are connected at their lower ends to the base 8 and to a platform 42 supported above the base 8 by means of the upwardly converging supporting uprights 43, 20 preferably four in number. The cross head 37 has laterally directed arms 38 and 39 for a purpose presently explained.

25 The uppermost piston 26 is secured in any suitable manner to the lower end of a tubular piston rod 44 which reciprocates through the bore and apertures 15 and 11, respectively, of the solid portion 13 of the pump cylinder and the base 8, respectively, and 30 freely through the aforesaid cross head 37. The upper end of said tubular piston rod is secured in any suitable manner to a cross head 45 slidably connected to the aforesaid guide rods 40 and 41 and provided with the laterally directed arms 46 and 47.

35 The intermediate piston 27 is secured in any suitable manner to the lower end of a piston rod 48 which reciprocates within the aforesaid tubular piston rod 44 and is secured at its upper end to a cross head 49 slidably embracing the aforesaid guide rods 40 and 41, and provided with laterally directed arms 50 and 51.

40 The piston operating means embodies among other characteristics three spur-rings 52 positioned co-axially in spaced relation to each other above the platform 42. Each spur-ring is inclosed within a suitable separate supporting housing 53 consisting of sections *a* and *b* which inclose the opposite sides

of the respective ring. Each section has ears 54 and these sections may be secured together by means of suitable bolts 55 passing through said ears 54.

45 The spur-rings are rotatable on roller bearings 56 interposed between the annular shoulders 57 on the sides of the rings and the internal annular shoulders 58 formed on the housing sections. These housings may be mounted on suitable bases 59 and secured by means of bolts or otherwise on the platform 42 with each housing provided with a lateral extension 60 to the outer sides of which suitable covers 61 may be secured by bolts 62 or otherwise.

50 A drive shaft 63 is journaled in bearings 64 formed in the lateral extensions 60 of the spur-ring housings and pinions 65 are keyed to this shaft 63, one pinion located within each of the extensions 60 for mesh with the respective spur-rings 52.

55 The shaft 63 may be driven through any suitable source of power. In the present embodiment of the invention, however, it is illustrated as being actuated by the combustion engine 66 mounted on a suitable support 67 secured to an extension 68 of the platform 42.

60 The uppermost cross head 49 has its laterally directed arms 50 and 51 connected by the pitman connections 69 and 70 which are eccentrically connected by the respective wrist pins 50' and 51' to the intermediate spur-ring 52 on opposite sides of the latter and which pitmen extend through the platform 42.

65 Pitman connections 71 and 72 are eccentrically connected by wrist pins 73 to the inner sides of the outer spur-rings and positioned 120° from the eccentric wrist pin connections of the aforesaid pitmen 69 and 70 with the intermediate spur-ring. The pitman connections 71 and 72 are connected at their lower ends to the arms 46 and 47 of the cross head 45.

70 Pitman connections 73 and 74 have connections at their lower ends with the arms 38 and 39 of the lowermost cross head 30 and at their upper ends they are eccentrically connected by wrist pins 76 to the outer sides of the outer spur-rings 52, being positioned substantially 120° from both of the eccentric connections of the other pitmen with the respective spur-rings.

75 It is evident that, when the sleeve 18 is lifted to a position above the openings 17 in the side walls of the pump cylinder, the load on the lowermost valved piston 28 will be considerably reduced because of the fact that these openings 17 are disposed above the water line and, by virtue of the up-stroke of said piston 28, forcing the water carried thereby out through the openings 17. While it may be desired to have these openings 17 arranged to have one of

the other pistons force the water out through the sides of the pump cylinder, the embodiment of the invention illustrated discloses that these openings are arranged for the 5 forcing of the water through the same by the lowermost piston 28 on the up-stroke of the latter. In any event, these openings 17 in the side walls of the cylinder are provided for coöperation with one of the pistons for the purpose of facilitating starting the pump and this is accomplished by reducing the load carried by the pistons and consequently reducing the load on the piston operating means by virtue of the water on 10 top of one of the pistons being forced out through the side walls of the cylinder above the water line. These openings may be gradually closed by the sleeve 18 at a predetermined time after the starting of the 15 pump until the pump is lifting to its full capacity.

What I claim is:

1. A pump comprising a cylinder provided with an opening arranged above the 25 water line, a plurality of reciprocating valved pistons in the cylinder, means for reciprocating the pistons, the lowermost piston on its up-stroke lifting the water and forcing the same out through said opening above the 30 water line to reduce the load and thereby facilitate starting the pump.

2. A pump comprising a cylinder open at each end and provided with openings adjacent its lower end above the water line, a 35 plurality of reciprocating valved pistons in the cylinder, means for reciprocating the pistons, the lowermost piston on its up-stroke lifting water and forcing the same out through said openings above the water line 40 to reduce the load on the remaining pistons and on the pump operating means to facilitate starting the pump, and means for closing said openings adjacent the lower end of the cylinder.

45 3. A pump comprising a cylinder open at each end and provided with openings adjacent its lower end above the water line, a plurality of reciprocating valved pistons in the cylinder, means for reciprocating the 50 pistons, the lowermost piston on its up-stroke lifting water and forcing the same out through said openings above the water line to reduce the load on the remaining pistons and on the pump operating means to 55 facilitate starting the pump.

4. A pump comprising a cylinder open at each end and provided with openings adjacent its lower end above the water line, a 60 plurality of reciprocating valved pistons in the cylinder, means for reciprocating the pistons, the lowermost piston on its up-stroke lifting water and forcing the same out through said openings above the water line to reduce the load on the remaining pistons 65 and on the pump operating means to facili-

tate starting the pump, a sleeve slidably embracing said cylinder and adapted to close said openings above the water line, and means for holding said sleeve over said openings.

5. A pump comprising a cylinder open at each end and provided with openings above the water line, a plurality of reciprocating valved pistons in the cylinder, means for reciprocating the pistons, the lowermost piston on its up-stroke lifting water and forcing the same out through the openings above the water line to reduce the load on the pump operating means so as to facilitate starting the pump, and a sleeve to close said 80 openings above the water line.

6. A pump comprising a cylinder open at each end and provided with openings above the water line, a plurality of reciprocating valved pistons in the cylinder, means for reciprocating the pistons, one of the pistons on its up-stroke lifting water and forcing the same out through said openings above the water line to reduce the load on the remaining pistons and on the pump operating 90 means to facilitate starting the pump, and means for closing said openings.

7. A pump comprising a cylinder open at each end and provided with openings in its side walls above the water line, a plurality 95 of reciprocating valved pistons in the cylinder, means for reciprocating the pistons, one of the pistons on its up-stroke lifting water and forcing the same out through said openings above the water line to temporarily reduce the load on the remaining pistons and on the pump operating means to facilitate starting the pump, a sleeve slidably embracing said cylinder, and adapted to open and close said openings of the cylinder above the 105 water line, an arm connected to said sleeve, a controlling arm connected to the aforesaid arm, and means for holding the controlling arm in different positions so as to hold said sleeve in its opening and closing relation with the openings in the side walls of the cylinder.

8. A pump comprising a pump cylinder, upper, lower and intermediate valved pistons mounted for reciprocation in the cylinder, means above the cylinder for reciprocating the pistons, telescopic piston rods between the reciprocating means and the upper and intermediate pistons, rods having connection with the reciprocating means and 115 extending parallel with the cylinder exteriorly thereof, a connection between the lower ends of said rods, and a connection between the last mentioned connection and the lowermost piston, all of the pistons being 120 arranged to be reciprocated in cycles substantially 120° under the influence of said piston reciprocating means, said cylinder having an opening arranged above the water line, the lowermost piston on its upper 130

stroke lifting the water and forcing the same out through said opening above the water line to reduce the load and thereby facilitate starting the pump.

- 5 9. A pump comprising a cylinder, a plurality of valved pistons mounted for reciprocation in the cylinder, cross heads having connections with the pistons, means for reciprocating said pistons including a plurality of spur-rings mounted coaxially in spaced relation, a separate housing for each spur ring, a drive shaft, pinions mounted on the drive shaft and having mesh with the respective spur-rings, pitmen eccentrically connected to each of the spur-rings and having connections with said cross heads so that upon operation of said drive shaft the pump may be operated.
- 10 10. A pump comprising a cylinder, a plurality of valved pistons mounted for reciprocation in the cylinder, cross heads having connections with the pistons, means for reciprocating said pistons including a plurality of spur-rings mounted coaxially in spaced relation, a driving shaft, pinions mounted on the driving shaft and having mesh with the respective spur-rings, and a plurality of pitman connections between each spur-ring and each cross head.
- 15 11. A pump comprising a supporting base, a pump cylinder depending from the platform, a plurality of valved pistons mounted for reciprocation in the cylinder, a plurality of uprights supported on the base, a platform supported by said uprights, a gear mechanism mounted on said platform, connections between the gear mechanism and the pistons to reciprocate the latter, means for operating the gear mechanism, the cylinder being constructed immediately above the water line to provide for reducing the load on the gear mechanism temporarily to facilitate starting the pump.
- 20 12. A pump comprising a supporting base, a pump cylinder depending from the platform, a plurality of valved pistons mounted for reciprocation in the cylinder, a plurality

of uprights supported on the base, a platform supported by said uprights, a gear mechanism mounted on said platform, connections between the gear mechanism and the pistons to reciprocate the latter, means for operating the gear mechanism, the cylinder having an opening therein immediately above the water line to reduce the load on the gear mechanism temporarily to facilitate starting the pump.

25 13. A pump comprising a cylinder provided with an opening above the water line, means for lifting water in the cylinder, the initial operation of the water lifting means forcing water out through said opening above the water line to reduce the load on the pump temporarily so as to facilitate starting the pump, and means for restoring the normal load capacity of the pump.

30 14. A pump comprising a cylinder open at each end and provided with openings intermediate its ends above the water line, a valved reciprocating piston in the cylinder to force water from the cylinder through said openings above the water line on the up-stroke of the piston so as to reduce the load on the pump operating means upon the initial operation of the same to facilitate starting the pump.

35 15. A pump comprising a cylinder open at each end and provided with openings intermediate its ends above the water line, a valved reciprocating piston in the cylinder to force water from the cylinder through said openings above the water line on the up-stroke of the piston so as to reduce the load on the pump operating means upon the initial operation of the same to facilitate starting the pump, and means for closing said openings above the water line.

In testimony whereof I affix my signature in the presence of two witnesses.

JAMES A. NORTON.
